DESIGN FOR A SHOE TREE

Milton L. Sturm, Chicago, Ill.

Application May 6, 1946, Serial No. 129,349

Term of patent 14 years

(Cl. D7—3)

To all whom it may concern:

Be it known that I, Milton L. Sturm, a citizen of the United States, residing at Chicago, in the county of Cook and State of Illinois, have invented a new, original, and ornamental Design for a Shoe Tree, of which the following is a specification, reference being had to the accompanying drawing, forming a part thereof.

I claim:

The ornamental design for a shoe tree, substantially as shown.

MILTON L. STURM.
